UNITED STATES PATENT OFFICE

158,721

INTERIOR CEILING PANEL

William Chavalas, Los Angeles, Calif., assignor to Fox West Coast Theatres Corporation, Los Angeles, Calif., a corporation of Delaware

Application June 10, 1949, Serial No. 3,186

Term of patent 14 years

(Cl. D68—1)

To all whom it may concern:

Be it known that I, William Chavalas, a citizen of the United States, residing in Los Angeles, in the county of Los Angeles and State of California, have invented a new, original, and ornamental Design for an Interior Ceiling Panel, of which the following is a specification, reference being had to the accompanying drawings, forming a part thereof.

I claim:

The ornamental design for an interior ceiling panel, substantially as shown.

WILLIAM CHAVALAS.
